A. W. HILSINGER
PAPER CUTTING MECHANISM

Filed June 30, 1922

Inventor
A. W. Hilsinger

By his Attorney

Thomas A. Hilsinger

UNITED STATES PATENT OFFICE.

ADIN W. HILSINGER, OF ORANGE, NEW JERSEY, ASSIGNOR TO HENRY BRADY, INC.,
A CORPORATION OF NEW JERSEY.

PAPER-CUTTING MECHANISM.

Application filed June 30, 1922. Serial No. 572,094.

To all whom it may concern:

Be it known that I, ADIN W. HILSINGER, a citizen of the United States, residing at Orange, in the county of Essex and State 5 of New Jersey, have invented certain new and useful Improvements in Paper-Cutting Mechanism, of which the following is a specification, reference being had therein to the accompanying drawing.

10 My invention relates to improvements in box making machines and has particular reference to and is illustrated in the accompanying drawings in its application to a web or paper feeding mechanism for passing 15 a sheet of material through the machine as the boxes or trays are cut and formed therefrom. The particular part of the machine to which this invention relates receives the sheet or web from a feeding device, the same passing intermittently or in 20 periodic steps to the cutting mechanism, from which the cut-off pieces are periodically fed through the machine for further operations.

25 In the accompanying drawing, I have illustrated in Fig. 1 in perspective, parts being broken away, feeding and cutting mechanism, embodying an application of my invention. Fig. 2 is a perspective view 30 of the knife and its support in inverted position. Fig. 3 is a perspective view of the knife and bedplate of the cutting-off mechanism, Fig. 4 is a cross-section on the line 4—4 of Fig. 2, and Fig. 5 is an enlarged 35 view of an adjustable bracket shaft holder.

5 indicates the frame of the machine suitably braced as indicated at 6 and provided with a shaft 7 upon which is mounted the pulleys 8—8' which are beneath the pulleys 40 9—9' upon the shaft 10, said shaft resting idly in the bearings 11—11' so that as the sheet feeds between the rollers 8—9 there is only frictional contact thereon, the rollers 8—8' rotating continuously. The shaft 7 is 45 provided with a pinion 12 meshing with the pinion 13 which in turn meshes with the pinion 14 driven by the pinion 15 from the main drive of the machine, and upon the shaft 7 is also mounted the sprocket wheel 50 16 carrying the chain 17 which drives the sprocket 18 upon the shaft 19 carrying the pulleys 20—20' which are also thereby continuously rotated.

21 indicates another shaft normally

raised by springs such as 22—22', said shaft 55 21 carrying pulleys 23—23' which by virtue of the action of the springs 22—22' are maintained out of contact with the pulleys 20—20', but hooks 24—24' are hung upon the shaft 21 and are at their lower extremity 60 pivotally mounted upon the shaft 25 which in turn is pivotally secured in the rods 26—26' secured upon the shaft 27, which shaft is provided with the lever 28 having a roller at one end 29 bearing upon the cam 65 30 on the shaft 31, so that periodically the rollers 23—23' are brought down in contact with the rollers 20—20' gripping the sheet therebetween and periodically feeding the same leftwardly as pieces of the sheet are 70 cut by the cutter.

The cutter consists of two base plates 32—33, separated sufficiently to permit the passage of the knife 34 retained in the upper plate 35, the same being shown in inverted position to better advantage in Fig. 2 where it will be seen that the knife 34 is higher at the centre than at the extremity, and is also pointed at the centre, thereby providing a shearing cut instead of a punch or straight cut, and it will also be observed by reference to Fig. 4 that the cutting edge of the knife is concave as indicated at 36 instead of convex as usual. 37—37' indicate suitable clamps or plates for retaining 85 the knife in position.

The face plates 32—33 are rigidly secured upon the machine and the knife portion is raised and lowered in the yoke 38 adapted to reciprocate vertically in the 90 guides 39—39' by virtue of levers such as 40 pivotally secured at the ends of the yoke 38 and eccentrically mounted upon the shaft 31, from which it will be seen that as the card is fed periodically to the knife, the knife descends while the card is stationary, cutting off a predetermined length and as the stroke of the knife is completed, the rollers 23—23' descend upon the card taking 95 each cut-off piece successively from the knife. The continuous rotation of the rolls 8—8' does not feed the card continuously as the card is fed to the rolls intermittently and is not gripped by the rolls sufficiently to take the card during its stationary or held period, but immediately the card moves leftwardly it is aided by the rolls 8—8' and by the pressure of the rolls 9—9' thereon,

thus the feed is intermittent. The operation of the knife is during the stationary period of the intermittent feed.

Of course it will be understood that various modifications may be made in the construction and arrangement of parts without departing from the spirit of the invention as claimed.

I claim:

- 10 1. In a discharge mechanism of the class described, discharge rolls normally separated by a spring and means for bringing

them together upon a blank to be discharged at predetermined intervals.

2. In a discharge mechanism of the class 15 described, discharge rolls normally separated by a spring and means for bringing them together upon a blank to be discharged at predetermined intervals, said means comprising hooks upon the axis of said rolls 20 and means for actuating said hooks.

In testimony whereof I hereunto affix my signature.

ADIN W. HILSINGER.
